Application May 6, 1939, Serial No. 84,847

To all whom it may concern:

Be it known that I, Charles R. Tost, a citizen of the United States of America, residing at Cranston, in the county of Providence and State of Rhode Island, have invented a new, original, and ornamental Design for a Cravat Holder or Similar Article, of which the following is a specification, reference being had to the accompanying drawing, forming a part thereof.

Fig. 1 is a front view, and Fig. 2 is an edge view of a cravat holder embodying my new design.

The dominant feature of the design is the pro-

vision of a wide clip member the upper and lower sides of which diverge substantially uniformly from end to end thereof, said sides of said wide clip member being spaced outwardly from the corresponding sides of the narrow clip member from end to end of said wide clip member, as shown.

I claim:

The ornamental design for a cravat holder or similar article, substantially as shown and described.
